CAN TREATING APPARATUS

Albert R. Thompson, San Jose, Calif., assignor to
 Food Machinery Corporation, San Jose, Calif.,
 a corporation of Delaware

Application March 13, 1934, Serial No. 715,279

20 Claims. (Cl. 126—272)

The present invention relates to can treating apparatus such as may be used in the canning industry for cooking, cooling, or otherwise processing or treating canned goods and the like, and is particularly concerned with the provision of a novel form of apparatus of this character for the continuous treatment of such goods, as distinguished from so called "batch" treatment thereof.

10 Among various undesirable features which have heretofore characterized continuous processing apparatus utilized for the purposes referred to, may be mentioned their general inability to accommodate cans of various sizes or shapes, thus necessitating duplication of equipment whenever 15 canned goods of various sizes or shapes is required to be processed. Moreover, the general limited capacity of such machines in proportion to their size is well known, and this characteristic requires the provision of large and ponderous equipment where any considerable capacity is desired. Obviously, the expense of such equipment and the provision of adequate floor space therefor present serious problems.

20 My invention is concerned with the provision of a continuous treating machine in which the foregoing disadvantages, as well as various others well known to the art, are largely overcome. For example, it may be stated that among the important objects of my invention are the provision 25 of a continuous treating apparatus which is of unusually large capacity, as well as the provision of such an apparatus which is capable of handling any size or shape of cans.

30 It is also an important object to provide a machine of this character which, although having a large capacity, is relatively small in size and occupies a minimum of floor space as compared with prior machines of comparable capacity.

35 Another object is to provide a continuous treating machine through which canned goods may be passed with substantially no agitation of their contents, this being a highly desirable feature, particularly in the processing of certain kinds of 40 canned foodstuffs which break down if they are over agitated during processing.

45 Another object is to provide a continuous treating machine through which canned goods may be passed without danger of abrasion to the can bodies, this being a disadvantage heretofore commonly met with. The ordinary tin cans in which such a large proportion of comestibles are marketed are customarily made of sheet iron overlaid with a very thin coating of tin which is 50 easily worn off, thereby exposing the sheet iron

body therebeneath, which not only make the cans unsightly, but exposes them to rust.

Still another object is to provide a can treating apparatus through which it is possible to pass the cans in indiscriminately timed arrangement, thereby eliminating the necessity for special timing or positioning mechanism in feeding the cans thereto.

5 A further object is to provide a combined cooking and cooling apparatus in which the speed of 10 operation of the cooker may be varied independently of the cooler and the feed, transfer and discharge devices, whereby the cooking period may be varied without affecting the rate of operation of the latter devices or the cooler.

15 Still further objects are to provide a machine for the purpose described in which the cans undergoing treatment cannot jam the machine irrespective of their shape or condition; which is of 20 greatly simplified construction; is comparatively inexpensive to build and maintain; and which is with highly efficient and thoroughly satisfactory in operation.

25 With these objects and advantages in view, as well as numerous others which will become more apparent as the description proceeds, it is believed that the invention may best be understood by reference to the accompanying drawings, in which:

30 Figure 1 is an elevational view, partly in section, of a practical application of the invention as embodied in both a cooker and cooler, which are illustrated as being interconnected for the continuous cooking and cooling of canned goods.

35 Figure 2 is a plan view of the same equipment.

Figure 3 is an irregular sectional view taken 35 along the line 3—3 of Figure 1.

Figure 4 is a detail view, partly in elevation and partly in section, showing the construction of the helical can advancing actuating mechanism, this being the same in both the cooker and the cooler.

40 Figure 5 is a detail cross sectional view taken, for example, along the line 5—5 of Figure 3, illustrating in larger scale the construction of the helical canway and carrier bars and showing the manner in which the cans are supported and advanced.

45 Figure 6 is a diagram illustrating the cycle of movement of the carrier bars.

50 Figure 7 is an elevational view of the driving gears and cam mechanism for operating the helical carrier bars in both the cooker and the cooler.

Figure 8 is a plan view of the gear and cam mechanism shown in Figure 7.

55 Figure 9 is an enlarged detail of the cam illustrated in Figs. 7 and 8.

The equipment illustrated comprises a cooker and cooler generally indicated at A and B respectively, and operatively associated with each other for the continuous cooking and cooling of 5 canned goods, which are passed successively therethrough.

The cooking unit A includes a vertical cylindrical shell 1 closed at its upper end by a transverse channel iron bridge member 2 and cover plates 3 and 4, the bridge member 2 also serving to support the bearings for the shafting shown 10 mounted thereon. In the lower portion of the shell 1 is an upwardly dished plate 5 which serves as a bottom closure for the cooker, and above 15 this plate there is disposed a steam coil 6 which is suitably apertured to permit discharge of steam therefrom for the purpose of heating the interior of the shell to a suitable cooking or sterilizing temperature.

20 The cooling unit also includes a vertical cylindrical shell 7 which may be open at its top as shown, if desired, and extending across its top is another channel iron bridge member 8 which also serves as a support for bearings, gears and 25 shafting mounted thereon. An upwardly dished plate 9 forms a bottom closure for the cooler, corresponding to the dished plate 5 of the cooker.

Drain pipes are provided at 10 and 11 for discharging, respectively, the condensed heating medium from the cooker and the used cooling liquid from the cooler.

The cans to be processed are introduced in indiscriminate order into the cooking or sterilizing chamber within the cooker shell through an inlet opening 12 by means of a rotary feed disc 13 situated, in part, in the inlet opening. The feed disc 13 is mounted for operation on a vertical shaft 14 about the center of which the disc rotates, and incoming cans may be delivered to the feed disc, 40 preferably in upright positions, by means of a chute 15 from which they move onto the upper surface of the disc for introduction into the cooker. The side walls of the chute 15 are extended and curved as at 16 and 17 so as to deflect the 45 incoming cans and cause them to move onto the upper extremity of a helical canway 18, down which the cans are periodically advanced in step by step movement by a carrier mechanism presently to be described.

50 Situated at the lower extremity of the cooker canway 18 and mounted on a vertical shaft 19, disposed intermediate the cooker and the cooler, is a rotary transfer disc 20 which projects on one side into the cooker through a discharge opening 21 in the cooker shell 1 and on the opposite side into the cooler through an inlet opening 22 in the cooler shell 7. The function of this disc is to transfer cans from the lower extremity of the cooker canway to the lower extremity of a 55 similar helical canway 23 in the cooler, from which point the cans are advanced upwardly over the cooler canway in the same manner as they are advanced through the cooker. During the travel of the cans through the cooler they are subjected to the action of a cooling medium, which may be in the form of a shower of cooling water, discharged in sprays from a shower pipe 24 disposed in the top portion of the cooler.

60 Situated near the top and partly within the cooler is a rotary discharge disc 25 mounted on a vertical shaft 26. This discharge disc is disposed in registration with the upper extremity of the cooler canway and arranged to receive cans therefrom and to discharge them from the cooler by 65 way of a discharge chute 27.

The directions of rotation of the feed, transfer, and discharge discs 13, 20 and 25, respectively, are indicated by suitable arrows in connection with each. These discs are connected together through shafts 28, 19 and 30, respectively journaled in suitable sets of bearings 31-31, 32-32 and 33-33, and the several bevel gears 34 to 41, inclusive, are driven by an electric motor 42 through the medium of a chain 43 trained around the motor sprocket 44 and a sprocket 45 mounted 10 on a shaft 46; a second chain 47 trained around a sprocket 48 on shaft 46 and sprocket 49 on the outer end of a shaft 50 which carries a bevel gear 51 on its inner end intermeshing with a bevel gear 52 keyed to the shaft 30.

15 Generally described, the can conveying mechanisms in the cooker and cooler include the canways 18 and 23, constructed to include a series of longitudinally extending interstices or slots within which operate a plurality of movable can lifting and carrying members driven in circuitous paths, so that they alternately rise above the canways into supporting engagement with the crowd of cans thereon to lift and carry the cans bodily during their forward movement, and then descend below the canways out of engagement with the cans to leave the latter resting upon the canways during the rearward movement of the carriers, whereby the cans are periodically advanced over the canways in step by step move- 30

ment.

Inasmuch as the can conveying mechanisms in the cooker and cooler are substantially identical, a description of that in the cooker will suffice for both. As best seen in Figures 1, 3 and 5, the 35 canway 18 is made up of a series of concentrically arranged helical stationary bars 53, which are radially spaced to form a slotted-grate-like helical can supporting table, these bars being supported at spaced intervals by a series of radially extending brackets 54 which are attached at their outer ends to the shell 1 and at their inner ends to vertical supporting standards 55.

The can advancing mechanism for advancing the cans over the canway includes a series of helical movable carrier bars 56 severally interspaced between the stationary bars and substantially co-extensive therewith. The movable carrier bars are mounted for operation by mechanism now to be described in circuitous paths, so that they 50 rise above the canways to lift and carry the cans bodily during their forward movement, and descend below the canways out of engagement with the cans to leave the latter resting upon the canways during the rearward movement of the 55 carrier bars.

As best seen in Figure 4, the carrier bars 56 are mounted upon a plurality of horizontal arms 57 projecting radially from a series of stacked hub members 58, the arms 57 being interspaced 60 between the stationary brackets 54 and arranged at stepped elevations in helical relation, similar to the steps of a spiral stairway. The hubs 58 are mounted upon a vertical shaft or axle 59 extending axially of the cooker shell and may be 65 interlocked with each other by means of lugs 60 which project into complementary recesses in adjacent hubs, so that only one of the hubs needs to be pinned to the shaft 59 to insure actuation of them all.

70 Both the movable carrier bars and the stationary can supporting bars 53 are elevated above their respective supporting arms 57 and brackets 54 by means of suitable spacers 61 and 62, respectively, in order to allow space for the movable 75

bars 56 to drop below the plane of the upper surfaces of the stationary bars 53 and also to permit them to be lifted above the stationary bars 53, as illustrated in Figure 5, without interference between the arms 57 and the bottom surfaces of the bars 53.

The driving mechanism for actuating the can carrier bars 56 is best illustrated in Figures 7, 8 and 9, and comprises a cast base member or supporting frame 63, a bearing 64, a chain sprocket 65, a beveled pinion 66, a bevel gear 67, a crank 68, a cam member 69 having a slotted arm 70, and a cam follower member 71 secured to the shaft 59 and having a slotted arm 72 and carrying a pair of cam rollers 73-73.

The sprocket 65 is driven continuously by a motor 74 through a variable speed transmission unit 75 and a driving chain 76. Speed adjustment of the transmission unit 75 may be made by means of the hand wheel 77. The crank 68, which is continuously rotated about the vertical axis of gear 67 engages the slot 70a in the lever arm 70 and causes that lever arm to oscillate through an angle of approximately 28 degrees about the center of the shaft 59. Cam member 69, being integral with lever arm 70 is likewise oscillated arcuately through a similar angle about its vertical center, which is coincident with the axis of shaft 59. This cam member has a pair of oppositely inclined cam faces 69a and 69b, upon which rest the cam rollers 73-73 respectively, which are carried by the follower 71, and it will be apparent that oscillation of the cam 69 will result in alternately lifting and lowering the follower 71 and the shaft 59 with it. It will also be seen that while the cam follower 71 is being repeatedly lifted and lowered by the action of the cam, it is also being rotatively oscillated arcuately about its vertical axis by the lever arm 70, which is provided with an elongated slot 72a engaging a crank pin 78 carried by and offset from the center of rotation of bevel gear 67.

The stacked hubs 58 rest upon the cam follower 71, which may be provided with a recess 79 engaging with the lug 60 on the lowermost hub.

The cycle of movement imparted to the can carrier bars 56 by the operation of the driving mechanism just described may best be understood by reference to Figure 6, in which their path of travel is diagrammatically illustrated. In this figure the line designated by reference numeral 56a represents the quasi-elliptical path followed by a point on the upper surface of one of the carrier bars 56 throughout one complete cycle of operation, while the line 53a represents the plane of the upper surface of one of the stationary bars 53.

As indicated by the arrows, the can carrier bars 56, as they begin their forward movement, rise above the stationary bars 53, thereby lifting the cans bodily from the canway, and then move forwardly thereby carrying the cans forwardly until near the end of the forward stroke when the carrier bars descend below the canway and thereby set the cans down on the stationary bars again. It is to be observed that the major axis of the quasi-elliptical path followed by the carrier bars is inclined from the horizontal in the direction of inclination of the stationary bars 53, and the carriers move over a relatively flat trajectory so that during the major portion of the forward travel of the carrier bars the cans are carried along in a descending path generally corresponding in pitch to that of the canway.

The advantage of so moving the carrier bars, as

will be apparent, is that it minimizes the head space required for the cans so that the convolutions of the canway may be spaced as closely together as possible, thereby utilizing the capacity of the treating chamber to maximum advantage.

The rearward or return movement of the carrier bars is along a path extending entirely below the canway, so that during this period the cans remain at rest on the canway. As the carrier bars approach the end of their return movement they begin to rise again and their upper surfaces come flush with the canway just at the beginning of their next forward movement, whereupon the cans are again lifted free of the canway and advanced another step, the cycle being successively repeated during operation of the machine.

It is believed that the construction and operation of the can conveying mechanism and its associated driving mechanism, as provided in the cooker, will now be apparent, and it will be understood that the corresponding mechanisms in the cooler are identical therewith, but are driven in an opposite direction in order to advance the cans upwardly along the cooler canway instead of downwardly, as in the cooker. The corresponding cycle of movement of the can carriers in the cooler would, accordingly, be exactly the reverse of that shown in Figure 6. Power may be supplied to the driving mechanism in the cooler from the shaft 46 driven by chain 43 from the motor 42.

It may be stated that it is not absolutely essential that the path of the can carrier bars be of the peculiar quasi-elliptical form shown in Figure 6, which is simply illustrated as being characteristic of the particular drive mechanism herein illustrated. While this particular motion is preferably used, and has been found in practice to be entirely satisfactory for the purpose, it will be understood that so far as the functions to be performed are concerned the path of movement might be rectangular or elliptical or some other form of cyclical or circuitous movement if desired, provided always that the carrier bars 56 rise above the stationary bars 53 during their forward movement and descend below the stationary bars during their return movement, and further provided that they do not rise above the stationary bars to such an extent as to cause the cans to strike the bars above. It will be obvious, therefore, that the particular drive mechanism disclosed may be modified, if desired, or other forms of drive mechanisms might be provided which would impart equivalent paths of movement to the carrier bars, and the term "circuitous" as used herein and in the claims is intended to be inclusive of any such endless paths irrespective of their particular shape, whether it be circular, elliptical, rectangular, or otherwise.

It is to be observed that the cooker and cooler are driven independently of each other, the former from the motor 74 through the variable speed transmission 75, and the latter from the motor 42, which may be of the constant speed type, and the feed, transfer and discharge discs 13, 20 and 25, respectively, are driven from the cooler drive. This is for the purpose of permitting variation in the speed of the cooker independently of the cooler and the feed, transfer and discharge discs.

As is well known, different products require different cooking periods, which may vary, for example, between 5 and 20 minutes or more depending upon the character of the product, and

in order to use the same equipment for processing a variety of products of different cooking time requirements it is necessary to make provision for varying the cooking period.

5 While it has heretofore been proposed to vary the cooking period by varying the speed of the cooker, it may be said that the maximum permissible speed of cookers of the character heretofore generally employed is seldom more than 100 cans 10 per minute, due to limitations imposed by the character of the feed, transfer and discharge devices. This may be explained by the fact that such apparatus is almost universally of the type in which the cans are advanced therethrough by 15 pocketed conveyors, such as the well known reel and spiral construction, thus requiring that the cans be fed, transferred and discharged by pocketed devices operated in accurately timed relation therewith. The result is that the speed 20 of the can advancing mechanism in the cooker cannot be varied without correspondingly varying the speed of the cooler and the feed, transfer, and discharge devices in order to maintain the proper timing, and the latter devices are not ordinarily 25 capable of handling more than 100 cans per minute without damaging the cans. Moreover, as the speed of the several mechanisms is increased, agitation of the can contents is likewise increased, and this may be highly undesirable. 30 When delicate products such as certain berries and fruits are being processed. Furthermore it will be appreciated that the cooler must be of the maximum size required to provide a treating path therein of sufficient length to properly cool the 35 cans when operated at the maximum speed, even though at lower speeds a smaller cooler would suffice.

By reason of these difficulties it has been the general practice in the past to operate the cooker 40 and cooler at a constant speed and to vary the cooking period by varying the length of the treating path through the cooker, as, for example, by providing it with a plurality of inlets or outlets through which the cans may be passed selectively 45 so as to shunt them around a portion of the treating path.

In the construction provided by the present invention, it has been found in actual practice that the can advancing mechanism will satisfactorily 50 operate at rates as high as 600 cans per minute without damage to the cans or their contents, and since the construction is such that the cans are received and conveyed through the cooker and cooler in indiscriminately timed arrangement, obviously there is no necessity for feeding, 55 transferring or discharging the cans in timed relation to the advancing mechanism, consequently the cooker speed may be varied at will while permitting the cooler, and the feed, transfer 60 and discharge discs to be driven at a constant selected speed commensurate with the speed of the canning line as a whole, and low enough to insure that no damage will result to the cans.

As illustrative of a practical example, the 65 cooker may be constructed to provide a twenty minute cook when driven at the rate of 150 cans per minute and the cooler, and feed, transfer and discharge discs may be driven at a constant speed to handle 150 cans per minute. If it is desired 70 to decrease the cooking period to five minutes, the cooker speed may be increased independently of that of the rest of the apparatus to 600 cans per minute, by adjustment of the variable speed transmission 75. Thus, while the same number 75 of cans per minute continue to pass through the

equipment, their rate of speed in passing through the cooker is quadrupled, thereby reducing the cooking period to one-quarter of the previous period.

It will thus be seen that the present invention provides great flexibility as regards the cooking period without the expense and complication of providing variable inlet or discharge mechanism, and at the same time the cooler need be only of sufficient size to cool the cans properly at the 10 minimum rate of speed of the cooker, since the constant speed of the cooler provides a constant cooling period irrespective of variations in the cooker speed. 15

Operation

15

Summarizing the operation of the apparatus described, the cans to be treated are fed into the cooker A preferably in upright positions by means of the feed disc 13, which delivers the cans directly onto the upper end of the helical cooker canway 18 in indiscriminate order, so that they are received by the canway in indiscriminately timed arrangement. Inasmuch as the canway is of a width approximating the radius of the cooking chamber so that it may accommodate a plurality of average sized cans transversely there-across and its entire surface is available for the reception of cans, it will be observed that substantially the maximum can holding capacity of the 20 cooker is utilized. Moreover, the width of the canway is such that it is not limited to any particular size or shape of can, and by reason of the absence of obstructions in the path of the cans passing over the canway it will be seen that there 25 is little or no possibility of the cans jamming any of the cooker mechanism to interfere with its operation, such as has heretofore sometimes occurred in prior machines of this character. 30

As the cans are delivered to the canway 18, 40 formed by the helical supporting bars 53, they rest stationary thereon until the cycle of operation of the drive mechanism actuates the cam 69 to lift the helical can carrier bars 56 upwardly through the interstices between the stationary 45 canway bars into supporting engagement with the cans, whereupon the cans are collectively lifted from the canway, as illustrated in Figure 5. While the carrier bars are thus being lifted, they are also rotated about the axis of the canway, so 50 that the cans are carried forward bodily over the canway until the carrier bars descend therebelow near the end of their forward travel, whereupon the cans are deposited back upon the canway where they again rest during the rearward movement of the carrier bars until the latter again engage with the cans to repeat the cycle of operations. 55

As the cans are thus advanced over the canway away from the feed disc 25, additional cans may be crowded continuously onto the canway by the feed disc to fill the space left by the preceding cans until the entire canway is filled, the continuous repetition of the cycle of operations described resulting in the periodical and collective 60 advancement of the cans bodily down the canway in step by step fashion by being successively lifted, carried forward along the canway a short 65 distance and set down upon the canway in recurrent cycles. The stream of cans is thus moved downwardly and helically through the cooker to the point of discharge in such manner that their contents receive a minimum of agitation, which, as heretofore pointed out, is frequently undesirable in the processing of certain kinds of food- 70 75

stuffs. Moreover, in addition, there can be no abrading action of any character on the can bodies such as might result in wearing away their tin coatings, thereby exposing the bodies of the cans.

5 As heretofore explained, the speed of operation of the can advancing mechanism may be varied independently of that in the cooler and the feed, transfer and discharge discs so as to provide a cooking period of desired length, this being accomplished by manipulation of the hand wheel 17 to adjust the variable speed transmission 15.

As the cans reach the lower end of the cooker canway they are delivered upon the upper surface of the rotating transfer disc 20, which feeds them into the cooler B through the cooler inlet opening 22 and onto the lower end of the cooler canway 23. Here the cans are again picked up and bodily carried upwardly over the cooler canway in periodical step by step fashion in the same 20 manner as they were previously advanced through the cooker, the canway in the cooler and its associated can advancing mechanism being substantially identical with that in the cooker, as heretofore stated. As the cans are discharged from 25 the upper end of the cooler canway they are received by the discharge disc 25, which delivers them into the chute 27, which directs them to any point desired.

The speed of operation of the can advancing 30 mechanism in the cooler may be selected so that the cans pass through the cooler in the period of time required for the degree of cooling treatment desired, and is in no way affected by variations in the speed of the cooker, and the feed, transfer 35 and discharge discs being driven from the cooler drive are driven at a speed corresponding to that of the cooler.

Having now described my invention and in what manner the same may be used, what I claim as 40 new and desire to protect by Letters Patent is:

1. In a can treating apparatus, a shell defining a treating chamber therewithin, a vertically disposed helical canway in said chamber, can carrying means associated with said canway for 45 transporting cans therealong, and means for operating said can carrying means into and out of supporting engagement with cans on said canway, to successively lift the cans from the canway, carry them bodily thereover, and lower them 50 back onto the canway in recurrent cycles.

2. In a can treating apparatus, a shell defining a treating chamber therewithin, a vertically disposed helical canway in said chamber, can carrying means associated with said canway for 55 transporting cans therealong, and means for elevating, lowering, and longitudinally oscillating said can carrying means with respect to the canway, and in timed relation to cause said can carrying means to rise and fall beneath cans on said canway to 60 successively lift them from the canway, carry them bodily thereover, and lower them back onto the canway in recurrent cycles.

3. In a can treating apparatus, a shell defining a treating chamber therewithin, a vertically disposed helical canway in said chamber, can carrying means associated with said canway for 65 transporting cans therealong, and means for operating the can carrying means over a circuitous path into and out of supporting engagement with cans on said canway to successively lift the cans from the canway, carry them bodily thereover, and lower them back onto the canway in recurrent cycles.

4. In a can treating apparatus, a shell defining a treating chamber therewithin, a vertically 70

disposed helical canway in said chamber, can carrying means associated with said canway for transporting cans therealong, and means for operating said can carrying means over a circuitous path to carry the same alternately above and below said canway whereby to lift and carry the cans bodily over the canway in step by step movement. 5

5. In a can treating apparatus, a shell defining a treating chamber therewithin, a vertically disposed helical canway in said chamber, can carrier means associated with said canway for transporting cans therealong, and drive means for vertically reciprocating said can carrier means and rotatively oscillating the same about the 15 axis of said canway to repeatedly lift, rotate forwardly, lower, and rotate backwardly said can carrier means relative to the canway whereby to successively lift the cans from the canway, carry them bodily thereover, and lower them 20 back onto the canway in recurrent cycles.

6. In a can treating apparatus, a shell defining a treating chamber therewithin, a vertically disposed helical canway in said chamber, can carrier means associated with said canway for transporting cans therealong, and means for imparting compound vertical reciprocation and rotative oscillation to the can carrier means about the axis of said canway, to cause said can carrier means to move in a cyclical path extending above 25 and below said canway, whereby to lift and carry the cans bodily over the canway in successive periodic steps. 30

7. In a can treating apparatus, a shell defining a treating chamber therewithin, a vertically disposed helical canway in said chamber, a vertically disposed helical can carrying device coaxially associated with said canway for transporting cans therealong, and drive means for vertically reciprocating said can carrying device and rotatively oscillating the same about the 35 axis of said canway to repeatedly lift, rotate forwardly, lower, and rotate backwardly said can carrying device relative to the canway whereby to successively lift the cans from the canway, carry them bodily thereover, and lower them 40 back onto the canway in recurrent cycles. 45

8. In a can treating apparatus, a shell defining a treating chamber therewithin, a vertically disposed helical canway in said chamber upon 50 which a plurality of cans may be supported in indiscriminately timed arrangement, and means for uniformly advancing said cans along said canway.

9. In a can treating apparatus, a shell defining a treating chamber therewithin, a vertically disposed helical can conveying mechanism in said chamber formed by a plurality of helically trending bars arranged to support a group of 55 cans thereon in indiscriminately timed arrangement, and means for imparting relative up and down and longitudinal movement to certain of said bars with respect to the others, for advancing cans bodily therealong. 60

10. In a can treating apparatus, a shell defining a treating chamber therewithin, a vertically disposed helical canway in said chamber upon which a plurality of cans may be supported in indiscriminately timed arrangement, can carrying means associated with said canway for collectively transporting said cans therealong, and means for operating said can carrying means into and out of supporting engagement with the cans on said canway to successively and collec- 70 75

tively lift the cans from the canway, carry them bodily thereover, and lower them back onto the canway in recurrent cycles.

11. In a can treating apparatus, a shell defining a treating chamber therewithin, a vertically disposed helical canway in said chamber for accommodating a group of cans thereon in indiscriminately timed arrangement, can carrying means associated with said canway for collectively transporting said cans therealong, and means for operating said can carrying means over a circuitous path to carry the same alternately above and below said canway into and out of supporting engagement with a group of cans thereon whereby to successively and collectively lift the cans from the canway, carry them bodily thereover, and lower them back onto the canway in recurrent cycles.

12. In a can treating apparatus, a shell defining a treating chamber therewithin, a vertically disposed helical canway in said chamber for accommodating a group of cans thereon in indiscriminately timed arrangement, can carrier means associated with said canway for collectively transporting said cans therealong, and drive means for vertically reciprocating said can carrier means and rotatively oscillating the same about the axis of said canway to repeatedly lift, rotate forwardly, lower, and rotate backwardly said can carrier means relative to the canway whereby to successively and collectively lift the cans from the canway, carry them bodily thereover, and lower them back onto the canway in recurrent cycles.

13. In a can treating apparatus, a shell defining a treating chamber therewithin, a vertically disposed helical canway in said chamber for accommodating a group of cans thereon in indiscriminately timed arrangement, a vertically disposed helical can carrying device coaxially associated with said canway for collectively transporting said cans therealong, and drive means for vertically reciprocating said can carrying device and rotatively oscillating the same about the axis of said canway to repeatedly lift, rotate forwardly, lower, and rotate backwardly said can carrying device relative to the canway whereby to successively and collectively lift the cans from the canway, carry them bodily thereover, and lower them back onto the canway in recurrent cycles.

14. In a can treating apparatus, a shell defining a treating chamber therewithin, a vertically disposed helical grate-like canway in said chamber for accommodating a group of cans thereon in indiscriminately timed arrangement, can carriers mounted for operation through the interstices in said canway for collectively transporting said cans therealong, and means for elevating, lowering, and longitudinally oscillating said can carriers with respect to the canway, and in timed relation to cause said can carriers to rise and fall beneath cans on said canway to successively and collectively lift them from the canway, carry them bodily thereover, and lower them back onto the canway in recurrent cycles.

15. In a can treating apparatus, a shell defining a treating chamber therewithin, a vertically disposed helical grate-like canway in said chamber for accommodating a group of cans thereon in indiscriminately timed arrangement, can carriers mounted for operation through the interstices in said canway for collectively transporting said cans therealong, and means for imparting compound vertical reciprocation and rotative oscillation to the can carriers about the axis of said

canway to cause said can carriers to move in a cyclical path extending above and below said canway into and out of supporting engagement with a group of cans thereon whereby to lift and carry the cans collectively and bodily over the canway in successive periodic steps.

16. In a can treating apparatus, a shell defining a treating chamber therewithin, a vertically disposed helical canway in said chamber including a plurality of helically trending parallel spaced can supporting bars for supporting a group of cans thereon in indiscriminately timed arrangement, a vertically disposed helical can carrier associated with said canway for collectively transporting said cans therealong, said can carrier including a plurality of helically trending parallel carrier bars interposed in the intervening spaces between said can supporting bars, and means for operating said carrier bars in a circuitous path to carry the same alternately above and below said can supporting bars into and out of supporting engagement with a group of cans thereon whereby to successively and collectively lift the cans from the supporting bars, carry them bodily thereover, and lower them back onto the supporting bars in recurrent cycles.

17. In a can treating apparatus, a shell defining a treating chamber therewithin, a vertically disposed helical canway in said chamber including a plurality of helically trending parallel spaced can supporting bars for supporting a group of cans thereon in indiscriminately timed arrangement, a vertically disposed helical can carrier associated with said canway for collectively transporting said cans therealong, said can carrier including a plurality of helically trending parallel carrier bars interposed in the intervening spaces between said can supporting bars, and drive means for vertically reciprocating said carrier bars and rotatively oscillating the same about the axis of said canway in timed relation to move the carrier bars in a circuitous path extending alternately above and below said can supporting bars into and out of supporting engagement with a group of cans thereon whereby to successively and collectively lift the cans from the supporting bars, carry them bodily thereover, and lower them back onto the supporting bars in recurrent cycles.

18. In a combined cooking and cooling apparatus, a cooker, a cooler, means in said cooker and cooler respectively for receiving and advancing cans therethrough, means for feeding cans to the cooker, means for transferring cans from the cooker to the cooler in untimed relation, means for driving said can advancing means and said feed and transfer means, and means for varying the speed of the can advancing means in the cooker independently of the speed of the can advancing means in the cooler and of the feed and transfer means.

19. In a combined cooking and cooling apparatus, a cooker, a cooler, means in said cooker and cooler respectively for receiving and advancing cans therethrough in indiscriminately timed arrangement, means for feeding cans to the cooker in indiscriminately timed arrangement, means for transferring cans from the cooker to the cooler in indiscriminately timed arrangement, means for driving said can advancing means and said feed and transfer means, and means for varying the speed of the can advancing means in the cooker independently of the speed of the can advancing means in the cooler and of the feed and transfer means.

20. In a combined cooking and cooling apparatus, a cooker, a cooler, means in said cooker and cooler respectively for receiving and advancing cans therethrough in indiscriminately timed arrangement, means for feeding cans to the cooker in indiscriminately timed arrangement, means for transferring cans from the cooker to the cooler in
- 5

indiscriminately timed arrangement, means for driving the can advancing means in the cooler and the feed and transfer means at a constant speed, and variable speed drive means for driving the can advancing means in the cooker.
